[57] CLAIM

The ornamental design for a tub rim, as shown and described.

DESCRIPTION

FIG. 1 is a perspective view taken from the top, front and right side of a tub rim embodying my new design; FIG. 2 is a top plan view thereof;

FIG. 3 is a front elevational view thereof, the rear being the same as the front;

FIG. 4 is a right side elevational view thereof, the left side being the same as the right side;

FIG. 5 is a cross-sectional view taken on line 5—5 of FIG. 2;

FIG. 6 is a cross-sectional view taken on line 6—6 of FIG. 2; and,

FIG. 7 is an enlarged cross-sectional view taken on line 7—7 of FIG. 2.

The fragmentary broken line representations of a portion of a bathroom island surrounding the tub in FIG. 1, and of a tub body in FIGS. 1, 2, 5, 6 and 7 are for the purpose of illustration only and form no part of the claimed design.
